Attorney

UNITED STATES PATENT OFFICE

WALENTY ZALEWSKI, OF KEWANEE, ILLINOIS

CURTAIN HANGER

Application filed May 20, 1930. Serial No. 454,046.

This invention relates to new and useful improvements in curtain hangers and has for its primary object to provide, in a manner as hereinafter set forth, a curtain embodying a novel construction and arrangement of parts whereby same may be expeditiously adjusted in a manner to adapt same for use on window frames of any width.

10 Another important object of the invention is to provide a curtain hanger of the aforementioned character embodying means whereby same may be securely mounted in position on a window frame without the use 15 of extraneous means such as nails or screws and will permit the quick removal of the device when desired.

Other objects of the invention are to provide a curtain hanger of the character described which will be comparatively simple in construction, strong, durable, efficient in use, neat and attractive in appearance and which may be manufactured at a low cost.

All of the foregoing and still further objects and advantages of the invention may 25 become apparent from a study of the following specification, taken in connection with the accompanying drawings wherein like characters of reference designate corresponding parts throughout the several views, and wherein:

Figure 1 is a view in front elevation showing a curtain hanger constructed in accordance with this invention mounted in position 35 on the upper portion of a window frame,

Figure 2 is a fragmentary detail view in longitudinal section showing the means for securing the telescopic rod section in adjusted position,

Figure 3 is a view in elevation showing the securing means for the telescopic rod section,

Figure 4 is a view in top plan showing a means associated with the free end of one of the rod sections for mounting same on the window frame,

Figure 5 is a sectional view taken substantially on the line 5-5 of Figure 2,

50 Figure 6 is a longitudinal vertical sec-

tional view through the inner end portion of one of the rod sections which carries the latching means, said means being removed therefrom.

Referring to the drawings in detail, it will be seen that the reference numeral 1 designates the upper portion of a window frame upon which the device constituting this invention is to be mounted. The curtain hanger comprises a pair of telescopically connected rods 2 and 3 of substantially C-shaped cross section, the inner portion of the rod 3 having formed therein a series of longitudinally spaced holes 4. As illustrated to advantage in Figure 6, the inner end portion of the rod section 2 has formed therein a hole 5 adapted to be selectively aligned with the hole 4 in the manner illustrated to advantage in Figure 2.

A pivotally mounted spring controlled latch 6 is supported in the rod section 2 adjacent the hole 5 and has formed integrally thereon a lug 7 for disposition through the hole 5 and one of the holes 4 with which said hole 5 is aligned for securing the rod sections 2 and 3 in adjusted position, as will be obvious. The spring for actuating the latch is designated by the reference character S.

A guide loop or eye 8 is also mounted longitudinally in the rod section 2 between the hole 5 and the adjacent end of said rod section and mounted for sliding movement through said guide eye is a keeper 9 adapted for slidably insertion beneath the adjacent end of the latch member 6 in a manner to retain same in inoperative position with the lug 7 withdrawn from the hole 4.

A supporting bracket 10 is provided for the outer end of the rod section 3 and is provided with a pair of projecting ears 11 for receiving the inturned end portion of said section 3 and another pair of rod sections (not shown) if desired. On the opposite side of the window frame is a supporting bracket 10 having operatively mounted thereon through the medium of the loop spring 11 the manually operable jaw 12 having teeth or spurs 13 on its inner side adapted to be embedded in the side of the

window frame 1. A pair of ears 13 extend outwardly from the bracket 10 over one of which is removably disposed adjacent in-turned end of the rod section 2.

5 The other of the ears 14 is to permit the mounting of another rod thereon if desired and as explained in the detailed description of the bracket 10.

In use, the keeper 9 is moved to the operative position illustrated in Figure 2 of the drawings to permit the sliding adjustment of the rod sections 2 and 3 with respect to each other. The bracket 10 is then mounted on the window frame and the rod section 3 mounted thereon. The rod sections are then adjusted longitudinally the proper length to permit the jaw 12 to be engaged with the opposite side of the window frame 1 with the teeth or spurs 13 embedded therein. The keeper 9 is then moved to inoperative position thus releasing the spring controlled latch member 6 and permitting the lug 7 to enter the holes 5 and 4 in the rod sections 2 and 3.

20 25 The spring loop 11 which supports the jaw 12 will permit slight adjustment of the rod section 2 and said section is mounted on the bracket 10 for the purpose of bringing the hole 5 into alignment with the closest 30 of the holes 4.

As will be seen in Figure 4 of the drawings, the spring loop 11 is mounted on the bracket 10 through the medium of a right angularly disposed tongue 15 extending 35 through an intermediate portion of the spring loop and terminating in a retaining flange 16. The jaw 12 is provided with an integral reduced handle portion 17 extending at an obtuse angle and projecting 40 through an intermediate portion of the spring loop 11. One end of the spring 11 is disposed in abutting engagement with the jaw 12 and the opposite end thereof is in abutting engagement with the crotch formed 45 by the bracket 10 and the tongue 15.

50 It is believed that the many advantages of a curtain hanger constructed in accordance with this invention will be readily understood, and although the preferred embodiment of the invention is as illustrated and described, it is to be understood that changes in the details of construction may be had which will fall within the scope of the invention as claimed.

55 Having thus described my invention, what is claimed as new is:

1. A curtain hanger of the character described comprising a pair of telescopically connected sections of substantially C-shaped 60 cross sections, said sections adapted for longitudinal adjustment relative to each other, means engaged with the free ends of the sections for removably mounting same on a window frame, a spring controlled latch member mounted on one of the sections and

engageable with the other section in a manner to secure said sections in adjusted position, and a keeper slidably mounted on said one section and engageable with the latch member in a manner to retain same in inoperative position.

2. A curtain hanger of the character described comprising a pair of sections telescopically connected together for longitudinal adjustment, one of said sections being provided with a series of longitudinally spaced holes, the other of said sections being provided with a hole adapted to be selectively brought into communication with the holes of the series, means detachably connected with the free end of the sections for removably mounting same on the window frame, a spring controlled latch member pivotally mounted on one of the sections, a lug formed integrally on said latch member and adapted to be projected through the aligned holes in a manner to secure the section against longitudinal movement, a guide eye mounted on said one section, and a keeper slidably mounted through the guide eye and engageable with the latch member in a manner to releasably retain same in inoperative position.

In testimony whereof I affix my signature:

WALENTY ZALEWSKI.
